[57] CLAIM

The ornamental design for a drainer tray or the like, substantially as shown.

DESCRIPTION

FIG. 1 is a top perspective view of a drainer tray or the like, showing my new design;
FIG. 2 is a top plan view thereof;
FIG. 3 is a side elevational view thereof;
FIG. 4 is a bottom plan view thereof; and
FIG. 5 is a cross-sectional view thereof taken along line 5—5 of FIG. 4.

FIG. 1

FIG. 2

FIG. 3

FIG. 4

FIG. 5
